Patented Sept. 26, 1961

191,404

INSECTICIDE SPRAYER OR SIMILAR ARTICLE

Robert C. Hudson, Glencoe, Ill., assignor to H. D. Hudson Manufacturing Company, Chicago, Ill., a corporation of Minnesota

Filed Apr. 2, 1959, Ser. No. 55,328

Term of patent 14 years

(Cl. D31—3)

FIGURE 1 is a perspective view of an insecticide sprayer or similar article embodying my new design;

FIG. 2 is a view in end elevation thereof on a reduced scale; and

FIG. 3 is a top plan view thereof.

The bottom of the insecticide sprayer is substantially plain.

I claim:

The ornamental design for an insecticide sprayer or similar article, substantially as shown and described.
